UNITED STATES PATENT OFFICE.

ABRUZZO MICHELE, OF PITTSBURG, PENNSYLVANIA, ASSIGNOR OF ONE-HALF TO BERNARD GASPORRO, OF PITTSBURG, PENNSYLVANIA.

CARTRIDGE.

No. 802,801.

Specification of Letters Patent.

Patented Oct. 17, 1905.

Application filed September 28, 1904. Serial No. 226,339.

To all whom it may concern:

Be it known that I, ABRUZZO MICHELE, a citizen of Italy, residing at Pittsburg, in the county of Allegheny and State of Pennsylvania, have invented certain new and useful Improvements in Cartridges; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an improved cartridge or shell for firearms; and it consists in forming the projectile or bullet with a circumferential recess capable of containing a quantity of water or other liquid and a series of perforations through the casing of the shell closed by plugs or stoppers adapted to be removed while the said projectile is leaving the casing, permitting the fluid to escape into the breech-chamber and the rifle-barrel, as will be fully set forth hereinafter.

In the accompanying drawings, Figure 1 is a central sectional elevation of a cartridge or shell constructed and arranged in accordance with my invention, a part of said view being shown in outside elevation. Fig. 2 is an outside elevation of the same. Fig. 3 is an end view thereof. Fig. 4 is a sectional view showing the manner of forcing the plugs out of the perforations.

To construct a cartridge or shell in accordance with my invention, I form the casing 1 from metal in the ordinary manner, consisting of a cylindrical shell open at the front and closed at the rear, at the center of which is placed the percussion-cap 2. The projectile 3 consists of a cylindrical body portion having a circumferential groove 5 and conical point 3, and arranged in the open end of the casing 1 in a manner that will entirely cover said groove, as will be seen at Fig. 1 of the drawings. Formed in the casing 1 and communicating with the groove 5 are a series of

perforations each of which is fitted with a soft-metal plug 6, a portion of each of which projects beyond the external and internal surfaces of the casing.

In operation a powder charge 4 is placed in the casing 1 and the projectile 3 seated therein. A suitable liquid, such as water or oil 7, is introduced through one or more of the perforations, the plugs 6 being removed for this purpose and then replaced when the compartment formed by the recess 5 and shell has been filled. When the powder charge 4 is exploded, the forward movement of the projectile will strip the plugs 6 from the perforations, as shown in Fig. 4, forcing a portion of the liquid through said perforations to cool the chamber in which the shell is confined and carrying the remaining portion of the liquid to the rifle-barrel, thereby preventing overheating of the same.

Slight modifications and changes may be made in the details of construction without departing from the spirit of the invention. Therefore I do not wish to confine myself to the exact details shown and described.

Having thus described my invention, what I claim, and desire to secure by Letters Patent, is—

The herein-described cartridge or shell, comprising the casing 1, provided with a percussion-cap 2, the powder charge 4 and projectile 3 arranged therein, the circumferential groove 5 formed about said projectile, the perforations fitted with soft-metal plugs 6 formed in said shell, said perforations being located with reference to the said groove 5 and a suitable liquid placed in said groove, all arranged and combined for service, substantially as and for the purpose described.

In testimony whereof I affix my signature in presence of two witnesses.

ABRUZZO MICHELE.
